UNITED STATES PATENT OFFICE.

WILLIAM SYLVESTER GREGORY, OF EAGLE ROCK, CALIFORNIA, ASSIGNOR OF ONE-HALF TO EVERETT B. LATHAM, OF LOS ANGELES, CALIFORNIA, AND ONE-HALF TO WM. GREGORY CO., OF LOS ANGELES, CALIFORNIA, A COPARTNERSHIP COMPOSED OF WM. S. GREGORY AND L. G. GREGORY.

WELL-DRILLING RIG.

Application filed January 23, 1922. Serial No. 531,264.

To all whom it may concern:

Be it known that I, WILLIAM SYLVESTER GREGORY, a citizen of the United States, and a resident of Eagle Rock, California, in the county of Los Angeles and State of California, have invented new and useful Improvements in Well-Drilling Rigs, of which the following is a specification.

This invention relates to well drilling and 10 pertains more particularly to a rig for drilling by the rotary method.

My invention has for its primary object the provision of a light weight and practically portable drilling rig, particularly 15 adapted to prospecting for oil in non-proven fields; particular attention being given to economy of fuel consumption, ease of operation and control by a minimum crew, elimination of accidents, such as twist-offs of 20 the drill pipe, and otherwise surmounting obstacles incident to the isolated territories in which prospecting is done.

Up to the present time, drilling and prospecting for oil has been almost solely 25 confined to proven fields, or fields in which surface indications or other conditions point strongly to the possibilities of finding oil. There exist, however, numerous localities in which geologists are of the opinion that oil 30 may be found but in which, owing to the fact that all indications have been erased, prospecting by present drilling equipment would prove extremely costly.

In drilling by the rotary method, a rotary 35 bit or drill is affixed to the end of a pipe, known as the drill pipe, and is lowered to the bottom of the hole and rotated by a rotary drilling table located at the surface. The drill pipe is raised and lowered as required 40 by means of a hoist, and the hoist, during drilling operations is so controlled that various percentages of the entire weight of the drill pipe are relieved from the bit according to the formation being drilled 45 and the allowable rotative speed. In a rig without sufficient flexibility of control, the drill pipe is apt to become twisted off, because of the bit becoming lodged before the driller has time to discontinue the rotation 50 of the drill pipe. Twist-offs are extremely costly, inasmuch as some of the drill pipe is left in the hole, and unless attempts to "fish"

out or otherwise dispose of the drill pipe are successful, the hole must be abandoned.

In view of the above, it is another object 55 of the invention to provide means in a drilling rig of the above character, whereby the tendencies for twist-offs to occur are practically eliminated, and whereby the rotative speed of the bit and the weight 60 upon it may be accurately controlled in accordance with the formation being drilled. It will be apparent that by so doing, drilling may be consistently expedited without fear or probability of twist-offs, and obviously 65 elimination of such accidents, and increased drilling speed result in decreased cost of drilling a hole.

In rotary drilling no casing is required to line the hole under normal conditions, and 70 as a result rotary drilling is less costly than is drilling by cable tool methods; in which methods the hole is cased as it progresses to prevent caving in the sides of the walls. While rotary drilling is known to be by 75 far the most economical, it has failed in most localities when used for drilling small wells, such as six inch bore. In drilling small bore wells the drill pipe is necessarily 80 of small diameter, and present types of rigs are not sufficiently flexible to so control the speed and "feed" of the drill as to prevent accidents.

It is therefore another object of the invention to provide a rig particularly adapted 85 to the drilling of small bore wells, and in carrying out my invention I employ novel features which render the rig extremely flexible and efficient.

During drilling operations, water is 90 pumped down through the interior of the drill pipe at a predetermined maintained pressure, and this water escapes through holes drilled in the bit, so that it enters the hole in proximity to the cutting edges of 95 the bit. This water picks up the cuttings from the bit and carries them in suspension to the surface. The water with cuttings in suspension is known in the art as "mud", and is pumped into a sump where it partially 100 settles, and from the sump it is again pumped into the drill pipe. Thus the cuttings of the bit are removed from the hole, and incidentally the walls of the hole are

- being continually "plastered", so that tendency to caving in is eliminated without the use of casing. The ability of water to carry particles in mechanical suspension decreases very rapidly with a decrease in velocity, and therefore it will be apparent that the pump circulating the mud must be very accurately controlled to maintain a given pressure and flow. The pressure and flow must be maintained practically constant regardless of the rate of drilling, inasmuch as a given velocity of returning water must be maintained in order to carry away the cuttings, regardless of increased or decreased amount thereof.
- It is therefore another object of the invention to provide a drilling rig capable of meeting the above requirements, as to pump pressure etc., independently of the rotative speed of the drill pipe, and independently of other factors.
- It will be understood in the consideration of the invention that heretofore steam engines have been found to be the most satisfactory means for operating well drilling rigs, and more than one separate engine is required. Usually an engine is used to operate the mud pump; another is used for operating the hoist; and for operating the rotary table to turn the drill pipe. As is well known, a steam engine has a wide range of torque, and is successful for operating the rotary table and hoist, inasmuch as full normal load can be developed at reduced speed by increasing the cut-off of the engine.
- My invention contemplates the use of internal combustion engines, preferably. The internal combustion engine is best adapted for use in the oil fields, inasmuch as no steam boiler is required, and it may burn gas, distillate, gasoline, or crude oil. Internal combustion engine power plants are therefore easily transported, are lower in first cost, and are generally adapted to use in oil fields or in isolated territories.
- Inasmuch as the internal combustion engine, however, will not develop full horsepower at reduced speed; is less flexible than a steam engine; and may be stalled by sudden increase in load, these engines have not been successful for use in driving rotary tables, hoists and the like. It is therefore another object of the invention to provide a drilling rig which may be operated by internal combustion engines successfully without danger of stalling the engine or engines, and with provision for meeting other requirements. For instance, occasions arise where it is advisable to impart increased torque to the drill pipe in order to make progress in hard formations. This may be readily done with a steam engine by increasing the cut-off, and in my improved rig I have made provision for imparting more than normal torque to the drill pipe while using internal combustion engines.

Also, during drilling, it occurs that the rotative speed of the drill pipe must be decreased while the torque is maintained constant, and it is another object of the invention to provide means for doing this.

With a view to obtaining increased efficiency and lighter weight per horse-power, it is another object of my invention to provide an internal combustion engine drilling rig in which a plurality of engines are used; it being understood that two engines of given power are lighter than one engine capable of developing the combined power output of the said two engines.

Other objects will appear hereinafter.

I have illustrated by the accompanying drawings a complete drilling rig, constructed in conformance with, and employing all the salient features of my invention. It is conceived that numerous modifications of design and arrangement of parts may be employed without departing from the spirit of, or enlarging the scope of my invention, within the appended claims.

In the said drawings.

Figure 1, is a plan view of a drilling rig constructed in conformance with, and embodying all the salient features of the invention.

Figure 2, is a view in section seen on line 2-2 of Fig. 1, looking in the direction indicated by the arrows, and showing the well being drilled, in section.

Figure 3, is a view mainly in vertical section of one of several clutches used in the rig.

Figure 4, is a view in section of said clutch seen on a line 4-4 of Fig. 3, looking in the direction of the arrows.

Figure 5, is a plan section of a part of the rig known as a triple gear.

Figure 6, is a view in section thereof seen on a line 6-6 of Fig. 5, looking in the direction indicated by the arrows.

Figure 7, is a plan view, parts being broken away, of a governor used in controlling the speed of the power plant.

Figure 8, is a plan view in elevation of a preferred form of power plant.

Figure 9, is a view thereof in section and elevation as seen on line 9-9 of Fig. 8, looking in the direction indicated by the arrows.

More specifically, my improved drilling rig includes essentially a rotary table 10, a hoist 11, mud pumps 12 and 13, and a single power plant 14 for driving the said table, hoist and pump.

The power plant drives a power shaft 15, to which the rotary table, the hoist and the mud pumps are operatively connected to be driven thereby. The said power shaft drives the rotary table through the medium of a set of bevel gears 16, and a universal shaft 17, provided with universal joints 18, whereby the rotary table may be disposed at a lower level than the main power shaft; the uni-

versal shaft extending at right angles to the main power shaft. Parts of the rig, with the exception of the rotary table, are here shown as supported by a unit frame 19, 5 made up of a plurality of I-beams 20, 21, 22 etc. Beams 21 and 22 extend parallelly along the rig with the main power shaft which is intermediate of the said beams; transverse braces 23, interconnecting the 10 parallel beams may be employed for supporting bearings 24, for the power shaft.

A rotary table drive shaft 25, carrying one of the bevel gears 16, is provided with a sprocket wheel 26, and a corresponding 15 sprocket wheel 27, is carried by the power shaft and is disposed adjacent the power shaft. Mud pumps 12 and 13 are driven by a common drive shaft 28, which in turn carries a sprocket wheel 29. Said sprocket 20 wheel is aligned with sprocket wheel 27 fixed to the power shaft, whereby said power shaft directly drives the pump drive shaft through the medium of a chain 30. The pump drive shaft carries a sprocket wheel 25 31, aligned with the sprocket wheel 26, of the rotary table drive shaft; whereby said pump drive shaft rotates shaft 25, through a chain 32.

Drive shaft 25 extends parallel with 30 power shaft 15, but is spaced therefrom and disposed intermediate of beams 20 and 21. Other braces 33 interconnect beams 20 and 21, and support bearings 34 of said drive shaft.

35 The mud pump drive shaft is provided with clutches 35 and 36, whereby either or both pumps may be cut out of operation, and it will be apparent that when the pumps are disconnected the power shaft may still continue to rotate the rotary table drive shaft.

The rotary table may be of any suitable 45 design, but is here shown as including a circular plate 37, formed on the under side with bevel gear teeth 37' and riding on ball bearings 38, carried on a base 39. The rotary table is capable of rotating a drill pipe 40, which is shown in Fig. 2 as extending down into a well 41, being drilled by the rig. To the lower end of the drill pipe is affixed a 50 rotary bit 41', which as it is turned by the drill pipe acts to bore deeper into the earth. The drill pipe is formed with an internal bore 40', so that mud may be pumped down to the bottom of the hole to escape adjacent 55 the bit.

To the upper end of the drill pipe is affixed a swivel 42; the lower end 42' of which is free to rotate with the drill pipe. The upper portion 43 of the swivel is capable of 60 remaining fixed against rotation and is held by a cable 44, which passes up over a hoist block (not shown) carried at the top of the usual derrick (not shown). A mud pump line 45 leads from the mud pumps to a point 65 adjacent the forward part of the rig, and

a flexible hose 46 connects said mud line with the swivel to convey mud to the bore of the drill pipe. The means shown and above described for supporting the drill pipe by the hoist, and means for conveying mud to the 70 drill pipe as above set forth, are common to the art and need no further description.

Owing to the height to which the derrick extends, the cable is of considerable length, and stretches considerably. It will be apparent, therefore, that by proper control of the hoist the percentage of the weight of the drill pipe caused to be placed upon the bit may be accurately varied to conform to the rate at which it is desired to have the 75 bit cut.

As a provision for safety and for other purposes hereinafter apparent, a special type of clutch 47, is interposed in the drive shaft for the rotary table. Said clutch is 85 hereinafter described more in detail as to construction and operation, and is capable of being set so that it will slip when a predetermined torque is reached or exceeded. Obviously, by provision of such a clutch the 90 possibility of twist-offs is eliminated.

The mud pumps may be of any usual type, and preferably at least two pumps are employed. As a general rule usual types of 95 mud pumps are non-reversible. One pump may be disconnected by throwing lever 48, which is operatively connected to and actuates clutch 35. The other pump may be disconnected by throwing lever 49, which actuates clutch 36. Thus either or both pumps 100 may be used, but normally only one pump is used, and the other is held in reserve.

It has been explained that the mud pumps must run at practically predetermined speed, although it is necessary at times to alter the maintained speed. The drill pipe's 105 rotative speed has to be changed repeatedly, and in order that both mud pump and the rotary table may be operated by a common power plant, but at independent speeds, I 110 have provided a multiple speed transmission 50 in the drive shaft of the rotary table. Any suitable type of transmission may be employed, and inasmuch as such devices are in common use and well known, no detailed illustration or description is considered to be required. Inasmuch as it is necessary at times to rotate the drill pipe in a reverse direction; as in the case of unscrewing 115 sections thereof, it is advisable that the transmission be provided with the usual reversing mechanism. Transmission 50 is controlled by a gear shift 50', which is here shown as being of the visible H-type, so that the driller may know at a glance the position of the gears. The shift is disposed so as to be convenient to the operator, and is operatively connected to the transmission by 120 suitable arrangement of rods and links (not shown).

125 130

To shift gears, the clutch in the drive shaft is thrown out, and then thrown in after the gears have been shifted. It is well known that a clutch must be provided for use with a transmission of the above described type, and it will be seen that by providing a clutch capable of slipping at a given torque; said clutch serves a plurality of useful purposes. By throwing out the clutch while the power shaft is running, the rotary table may be stopped without affecting the operation of the pumps.

The power plant may be of any suitable type, but in the embodiment shown and described, internal combustion engines are employed. While a single engine of this type might be used, my invention contemplates the use of a plurality of engines connected in a novel manner hereinafter set forth to provide a power plant of greater flexibility and economy.

In the embodiment shown, three internal combustion engines, 51, 52 and 53, in cruciform arrangement are mounted on beams 54, forming substantially a part of the frame of the rig.

By providing three engines capable of developing the maximum horse power required instead of using one engine, greater flexibility and economy results. Ordinarily two of the said engines will be sufficient to operate the rig. When an extra heavy load is to be met the entire three engines may be used. In the case of a very light load only one engine will be required. By using two engines for usual conditions the third may be held in reserve in case repairs are required on either of the other engines.

Each engine is provided with a shaft 51', 52' and 53', connecting with a triple gear transmission 54; whereby all engines may collectively drive the main power shaft. Engine 51 extends in alignment with the main power shaft and is capable of driving said power shaft direct.

A hoist drive shaft 54' is provided and is aligned with and connected to the main power shaft by a clutch 55. This clutch, as in the case of clutch 47, is capable of slipping when a predetermined load is reached in order to prevent the hoist stalling the engine or engines driving it, as well as to prevent injury to the cable, etc. Intermediate of the clutch and hoist, a multiple gear transmission 56, is interposed in the hoist drive shaft. Said transmission is provided with a gear shift 57, disposed adjacent shift 50', and connected to the transmission by proper arrangement of rods and links (not shown). The clutch is thrown out when it is required to change gears, and thus serves a dual purpose. A sprocket wheel 58 is fixed to the end of the hoist drive shaft in alignment with a sprocket 59, carried by a hoist drum 60; whereby the drive shaft ro-

tates the drum through a sprocket chain 61.

Transmission 56 is provided with the usual plurality of forward speeds common to such devices, and is also capable of reversing the hoist drum. When the cable is to be lowered into the well with little or no weight attached, the reverse speed is used so that it may be positively unwound from the drum, and allowed to descend easily of its own weight. When a heavy load is being lowered by the hoist, a hoist brake 62 may be employed to retard the speed of the drum; it being understood that in such a case the drum is thrown out of engagement from all driving parts by means of a hoist clutch lever 63, acting on a hoist clutch (not shown) common to usual hoists. Obviously, any appreciable weight may be lowered with the hoist in operative connection with the main power shaft through the reverse position of its transmission. In such case the load on the cable will assist the power plant.

Other objects of the multiple speed transmissions provided, for both the rotary table and the hoist, will be apparent when it is explained that it is primarily intended to run the engines of the power plant at constant and full speed under normal conditions so that a pump, or pumps, may operate at constant and full speed. By shifting gears in the transmissions either the hoist, or the table, or both may run each at speeds varying with the pump, or at speeds varying with the pump and with each other.

Each engine of the power plant is controlled by a governor 64, of any usual type and not herein described in detail. Said governor, however, is provided with the usual oscillating shaft 65, as shown particularly in Fig. 7. This shaft advances or is retracted a partial revolution by corresponding increase or decrease of the rotative speed of the engine. To the shaft 65 is attached an arm 66, which oscillates therewith. In this form of governor, as in all centrifugal governors, the weights (not shown), are resisted by a spring 67, which in this case bears against arm 66. The tension of the spring determines the speed of the engine by predetermined the speed at which the centrifugal force of the governor weights will resist said spring and move said arm. The arm is connected to a throttle 68 by a link 69.

For manual control of the speed of the engine, said spring is disposed within a circular housing 70, which is internally threaded to receive a threaded plunger 71, which bears against the spring. The plunger is provided with a sprocket wheel 72, which as it turns, advances or retracts the plunger relative to the spring to change its tension. All three engines are controlled simultaneously by the driller through a quadrant 73,

conveniently located, and preferably disposed adjacent the other controls of the rig. Said quadrant is capable of turning a main governor control shaft 74, through a shaft 75 and bevel gears 76 and 77. Shaft 74, is provided with bevel gears 79 and 80, and a sprocket wheel 81. The latter is connected by a chain to the sprocket wheel on the governor of the engine 51. Bevel gear 79 meshes with a bevel gear 78, carried on a shaft 82, having a sprocket wheel 83 and chain 84, to turn the sprocket on the governor of the engine 52. Similarly, a bevel gear 85, on a shaft 86; having sprocket 87 and a chain 88, meshes with bevel gear 79, whereby the sprocket wheel on the governor of engine 53 is actuated.

Thus all engines are controlled simultaneously as to their predetermined speed. Now it is well known that by manually controlling an engine through a centrifugal governor, the said engine will run at constant speed under variable load and will continue so as long as the load to which it is subject does not exceed the maximum horse power at the given speed. With the mud pump in operation the speed thereof will not vary with the starting and stopping of the rotary table and hoist. At any time the rotary table or hoist is put in operation it will immediately attain maximum speed.

Now it will be seen that by operating one, two or three engines, as required, the power plant may operate at one-third, two-thirds, or full load with equal thermal efficiency, particularly inasmuch as the engine or engines running do not have to drag along the engines or engine not running under power.

As will be seen by reference to Fig. 5, the main power shaft 15 extends directly through the triple gear transmission, and therefore engine 51 drives the power shaft directly. Engine 51 may be disconnected from the shaft by throwing a clutch 89, interposed in shaft 51'. Shaft 52' is similarly equipped with a clutch 90, and likewise shaft 53' is equipped with a clutch 91. Clutches 89, 90 and 91, respectively are operated by levers 92, 93 and 94, respectively, which are disposed so as to be convenient to the operator of the rig. These levers are connected to their respective clutches by rods and links (not shown).

The triple gear transmission 54, is designed to allow shaft 15 to rotate without rotating 52' and 53'. Referring now to Figs. 5 and 6, said transmission includes a housing 95 of cruciform outline, and formed with four extending bearings 96, for shafts 51', 52' and 53'. Shaft 51' is formed with a spline 97, over which rides a sliding collar 98, formed with a rectangular recess 98'. Said shaft carries a bevel gear 99 fixed thereto, and formed with a projecting dog 100, which is capable of entering the recess to

cause said collar to become locked to the bevel gear and shaft 51'. The collar is operated by a shift fork 101, oscillated by a rock-shaft 102. Lever 103, disposed adjacent levers 92 etc. is employed by the operator to shift said collar. Thus by throwing lever 103 the bevel gear 99 will rotate with shaft 51'. Both shafts 52' and 53', carry bevel gears 104 and 105, respectively keyed thereon, and in continual mesh with gear 99.

The clutches employed in the power plant may be of any suitable construction, but are preferably the same in construction as clutches 47 and 55. The last mentioned clutches are thrown by levers 106 and 107, respectively, through a plurality of rods and links (not shown).

In Figs. 3 and 4, I have shown one of the said clutches more in detail. The clutch includes a drum 110, and a pair of discs 111 and 112. Shaft 15, on which this clutch is shown interposed is divided as at 113, into sections 114 and 115. Disc 112 is secured to section 114, by a key 116 which holds it against rotation or longitudinal movement thereon. Drum 110 is secured to section 115, by a key 117, and is provided with an integral collar 118 encompassing section 115 of the shaft. With the clutch "thrown out", section 115 and drum 110 will revolve, while section 114 and the disc may remain motionless. It is the purpose of the clutch to bring drum 110 into frictional engagement with the discs, so that section 114 of the shaft will be rotated by section 115. Drum 110 carries an annulus 119, of brake material, such as wood or other material having a high friction coefficient, and said annulus is reenforced by an inner annulus 120, of metal. Discs 111 and 112 are capable of being retracted from each other, or advanced toward each other. It will be apparent that, with the discs advanced toward each other until they engage corresponding surfaces 121 and 122, of annulus 119, section 115 will rotate section 114. Disc 111 is moved by worm gears 123, which are rotatably mounted on disc 112, and are fixed to rotatable shafts 124 passing through said disc and screw-threaded into disc 112 as at 125. It will be apparent now that when gears 123 are rotated upon their axes in one direction, disc 111 will be moved farther away from disc 112, and thus out of engagement with the annulus 119. Said gears are each rotated by a rack 126, formed with teeth 127, pitched at proper angle, whereby the rack upon sliding will slowly rotate the corresponding gear, but the gear will lock against the teeth when any force tends to advance it. Thus while disc 112 may be moved easily by the sliding racks, it is incapable of movement when the racks are stationary. Said racks

123
125
126
127
130

are carried by a shaft collar 128 slidably mounted on section 114, of the shaft. The racks ride into bores 129, formed within disc 112 and therefore said shaft collar is substantially a part of said disc and rotates therewith. The shaft collar is actuated by a clutch collar 130, loosely encompassing the shaft collar, and riding in an annular depression 131. Trunnions 132 are formed 10 on the clutch collar, and are disposed in trunnion bearings 133, formed in a pair of encompassing straps 134, joined as at 135, to form a shift lever 136. The shift lever connects with its corresponding control lever, disposed conveniently to the operator 15 of the rig.

It will be apparent that the clutch may be thrown in very gradually and may be "set" at any desired point. The position 20 at which it is set determines the pressure with which discs 111 and 112 are clamped to annulus 119, and thereby the torque at which the clutch will "slip" is determined.

The operation of the various parts of the 25 rig being hereinbefore explained; the operation of the rig as a whole may be better understood from the following:

Engine 51 is first started, and with its 30 clutch thrown in, it will drive the power shaft directly. Assuming the drill pipe is assembled and in the well and ready for drilling, it may be rotated by throwing in the clutch which controls it. The clutch on one mud pump at least is in at all times, 35 and thus mud is kept in circulation continually, as explained. The transmission controlling the speed of the drill pipe is set in gear. The transmission controlling the speed of the hoist drum is set in 40 any desired forward gear, but preferably in low gear, so that the drill pipe may be quite accurately controlled. It is understood of course that the weight of the drill pipe is held by the cable and the percentage 45 of weight allowed to bear on the drill is governed by controlling the hoist drum, preferably with the brake and the usual hoist-drum clutch common to such hoists. The clutch in the hoist drum shaft is left 50 "in" during drilling.

The clutch in the rotary table drive shaft 55 is thrown "in" slowly, and set so that it rotates the drill pipe without slipping, but will slip when the load increases slightly. The hoist is manipulated to give the required feed to the drill and thus drilling is started. The driller generally knows 60 from samples taken, the "feel" of the rig, or from data on hand, the nature of the formation being drilled. He also endeavors to keep track of decreasing sharpness 65 of the drill. Should the clutch in the rotary table drive shaft slip, he is aware that he is either encountering harder formation or the drill is not cutting properly.

The drill may be raised slightly off the bottom of the hole, and lowered again to make sure it is properly positioned. If the clutch continues to slip it is set for a higher torque. If now, a hard formation has been 70 reached and one engine tends to slow down, another engine is "cut in", in the manner described. Should the driller desire to "feed" faster, a little more slack is allowed in the cable to put more weight on the drill. 75 Should the drill now cause the clutch to slip, with the clutch set, it will indicate too great a load on the drill for the speed. It is now desired to decrease the rotative speed of the drill, while allowing the pumps to 80 continue at full speed. This is done by putting the rotary table transmission in "second" or "low". Should the clutch slip in "low" it will be necessary to relieve some of the weight from the drill pipe, inasmuch as slipping of the clutch, when well set in low gear, is an indication that a torque has been reached which it would be dangerous for the drill pipe to exceed.

With the hoist transmission in "low", the 85 cable may be very accurately controlled, while for fast raising of a light weight, a higher gear is employed.

The above description illustrates the 90 flexibility of the rig as a whole, but is not necessarily typical of all conditions. A wide range of combinations of speeds, 95 "feeds", pump pressures etc., may be obtained, and the manner of setting the clutches and gears, and otherwise controlling 100 and "feeling out" the rig and the drilling conditions is practically optional with the driller.

It will be apparent, however, that the rotative speed of the pumps, hoist and rotary 105 table, may be independently controlled. The speed at which one or more engines begin to slow down may be taken as a gauge; or the point at which the clutches slip; with consideration of the gear ratio used, may 110 be taken as a gauge.

In summarizing the advantages of the rig 115 it may be said that it is sufficiently flexible and sensitive to not only provide for faster drilling and greater fuel economy, but it will enable one skilled in the art to "feel" the bottom of the well, as it were. Also, one man may control the feed and speed of the drill so as to increase the time which a drill may be kept sharp.

It will be apparent that by the provision 120 of a governor controlled prime mover for driving the rig, and by controlling the speed of the power shaft by controlling the governor; all parts will operate at constant respective speeds regardless of change in the load. When it is known that one engine 125 will carry the load, only one engine is put in operation. Should a clutch slip, or should more power be required on short 130

notice, it is only necessary to operate two levers in conjunction; one to relieve the load for an instant, and the other to "cut in" another engine.

- 5 It will be apparent now that I have provided a drilling rig capable of carrying out the objects set forth, and possessing the advantages set forth, and while I have shown and described a specific construction 10 and arrangement of parts, I do not limit myself thereto, but may alter the construction and arrangement of parts, and I may variously combine all, or a part of all the salient features of my invention in a single 15 operative rig, as occasion requires, without departing from the spirit of, or enlarging the scope of my invention, within the appended claims.

I claim:

- 20 1. A well drilling rig, including a rotary table capable of rotating a drill pipe, a hoist capable of raising and lowering the drill pipe, a mud pumping device, a power shaft operatively connected to and capable of rotating said rotary table, said hoist and said mud pumping device simultaneously, a multiple gear interposed between said rotary table and said power shaft, and another multiple gear interposed between said hoist and 25 said power shaft.

2. A well drilling rig, including a rotary table capable of rotating a drill pipe, a hoist capable of raising and lowering the drill pipe, a mud pumping device, a power shaft operatively connected to and capable of rotating said rotary table, said hoist and said mud pumping device simultaneously, and a multiple gear interposed between said rotary 30 table and said power shaft.

3. A well drilling rig, including a rotary table capable of rotating a drill pipe, a hoist capable of raising and lowering the drill pipe, a mud pumping device, a power shaft operatively connected to and capable of rotating said rotary table, said hoist and said mud pumping device simultaneously, and a multiple gear interposed between said hoist and said power shaft.

4. A well drilling rig, including a rotary table capable of rotating a drill pipe, a hoist capable of raising and lowering the drill pipe, a mud pumping device, a power shaft operatively connected to and capable of rotating said rotary table, said hoist and said mud pumping device simultaneously, a multiple gear interposed between said rotary table and said power shaft, and another multiple gear interposed between said hoist and said power shaft; said multiple gears 55 each having a plurality of forward speed positions, a neutral position and a reverse position.

5. A well drilling rig, including a rotary table capable of rotating a drill pipe, a hoist capable of raising and lowering the 60

drill pipe, a mud pumping device, a power shaft operatively connected to and capable of rotating said rotary table, said hoist and said mud pumping device simultaneously, and a multiple gear interposed between said rotary table and said power shaft; said multiple gear having a plurality of forward speed positions, a neutral position and a reverse position.

6. A well drilling rig, including a rotary table capable of rotating a drill pipe, a hoist capable of raising and lowering the drill pipe, a mud pumping device, a power shaft operatively connected to and capable of rotating said rotary table, said hoist and said mud pumping device simultaneously, and a multiple gear interposed between said hoist and said power shaft; said multiple gear having a plurality of forward speed positions, a neutral position and a reverse position.

7. A well drilling rig, including a rotary table capable of rotating a drill pipe, a hoist capable of raising and lowering said drill pipe, a power shaft operatively connected to and capable of operating said rotary table and said hoist simultaneously, a multiple gear interposed between said rotary table and said power shaft, and another multiple gear interposed between said hoist and said power shaft.

8. A well drilling rig, including a rotary table capable of rotating a drill pipe, a hoist capable of raising and lowering said drill pipe, a power shaft operatively connected to and capable of operating said rotary table and said hoist simultaneously, and a multiple gear interposed between said rotary table and said power shaft.

9. A well drilling rig, including a rotary table capable of rotating a drill pipe, a hoist capable of raising and lowering said drill pipe, a power shaft operatively connected to and capable of operating said rotary table and said hoist simultaneously, and a multiple gear interposed between said hoist and said power shaft.

10. A well drilling rig, including a rotary table capable of rotating a drill pipe, a hoist capable of raising and lowering said drill pipe, a power shaft operatively connected to and capable of operating said rotary table and said hoist simultaneously, and a multiple gear interposed between said hoist and said power shaft, and another multiple gear interposed between said rotary table and said power shaft; said multiple gears each having a plurality of forward speed positions, a neutral position and a reverse position.

11. A well drilling rig, including a rotary table capable of rotating a drill pipe, a hoist capable of raising and lowering said drill pipe, a power shaft operatively connected to and capable of operating said

rotary table and said hoist simultaneously, and a multiple gear interposed between said rotary table and said power shaft; said multiple gear having a plurality of forward speed positions, a neutral position and a reverse position.

12. A well drilling rig, including a rotary table capable of rotating a drill pipe, a hoist capable of raising and lowering said drill pipe, a power shaft operatively connected to and capable of operating said rotary table and said hoist simultaneously, and a multiple gear interposed between said hoist and said power shaft; said multiple gear having a plurality of forward speed positions, a neutral position and a reverse position.

13. A well drilling rig, including a rotary table capable of rotating a drill pipe, a hoist capable of raising and lowering the drill pipe, a pumping device, a power shaft operatively connected to and capable of operating said table, said hoist and said pump simultaneously, a clutch interposed between said power shaft and said rotary table, a second clutch interposed between said power shaft and said hoist, and a third clutch interposed between said power shaft and said mud pumping device; each of said clutches being capable of slipping when subject to a torque in excess of that predetermined.

14. A well drilling rig, including a rotary table capable of rotating a drill pipe, a hoist capable of raising and lowering the drill pipe, a pumping device, a power shaft operatively connected to and capable of operating said table, said hoist and said pump simultaneously, and a clutch interposed between said power shaft and said rotary table; said clutch capable of slipping when subject to a torque in excess of that predetermined.

15. A well drilling rig, including a rotary table capable of rotating a drill pipe, a hoist capable of raising and lowering the drill pipe, a pumping device, a power shaft operatively connected to and capable of operating said table, said hoist and said pump simultaneously, and a clutch interposed between said power shaft and said hoist; said clutch capable of slipping when subject to a torque in excess of that predetermined.

16. A well drilling rig, including a rotary table capable of rotating a drill pipe, a hoist capable of raising and lowering the drill pipe, a pumping device, a power shaft operatively connected to and capable of operating said table, said hoist and said pump simultaneously, and a clutch interposed between said power shaft and said pumping device; said clutch capable of slipping when subject to a torque in excess of that predetermined.

17. A well drilling rig, including a rotary table capable of rotating a drill pipe, a hoist

capable of raising and lowering the drill pipe, a power shaft connected to and capable of operating said table and said hoist simultaneously, and a clutch interposed between said rotary table and said power shaft; said clutch capable of slipping when subject to a torque in excess of that predetermined.

18. A well drilling rig, including a rotary table capable of rotating a drill pipe, a hoist capable of raising and lowering the drill pipe, a power shaft operatively connected to and capable of operating said table and said hoist simultaneously, and a clutch interposed between said hoist and said power shaft; said clutch capable of slipping when subject to a torque in excess of that predetermined.

19. In a well drilling rig, including a rotary table capable of rotating a drill pipe, and an auxiliary power driven apparatus; a power shaft operatively connected to and capable of operating said table and said auxiliary simultaneously; and a clutch interposed between said power shaft and said table; said clutch capable of slipping when subject to a torque in excess of that predetermined.

20. A well drilling rig, including a rotary table capable of rotating a drill pipe, a hoist capable of raising and lowering the drill pipe, a pumping device, a power shaft operatively connected to and capable of operating said table, said hoist and said pump simultaneously, a clutch interposed between said power shaft and said rotary table, a second clutch interposed between said power shaft and said hoist, and a third clutch interposed between said power shaft and said pumping device; each of said clutches being capable of slipping when subject to a torque in excess of that predetermined, and adjusting means operable while said clutches are in motion, whereby the torque at which they will slip may be predetermined.

21. A well drilling rig, including a rotary table capable of rotating a drill pipe, a hoist capable of raising and lowering the drill pipe, a pumping device, a power shaft operatively connected to and capable of operating said table, said hoist and said pump simultaneously; and a clutch interposed between said power shaft and said rotary table; said clutch capable of slipping when subject to a torque in excess of that predetermined, and adjusting means, operable when said clutch is in motion, whereby the torque at which it will slip may be predetermined.

22. A well drilling rig, including a rotary table capable of rotating a drill pipe, a hoist capable of raising and lowering the drill pipe, a pumping device, a power shaft operatively connected to and capable of operating said table, said hoist and said pump

simultaneously, and a clutch interposed between said power shaft and said hoist; said clutch capable of slipping when subject to a torque in excess of that predetermined, and adjusting means, operable while said clutch is in motion, whereby the torque at which it will slip may be predetermined.

23. A well drilling rig, including a rotary table capable of rotating a drill pipe, a hoist capable of raising and lowering the drill pipe, a pumping device, a power shaft operatively connected to and capable of operating said table, said hoist and said pump simultaneously, and a clutch interposed between said power shaft and said pumping device; said clutch capable of slipping when subject to a torque in excess of that predetermined, and adjusting means, operable while said clutch is in motion, whereby the torque at which it will slip may be predetermined.

24. A well drilling rig, including a rotary table capable of rotating a drill pipe, a hoist capable of raising and lowering the drill pipe, a power shaft operatively connected to and capable of operating said table and said hoist simultaneously, and a clutch interposed between said rotary table and said power shaft; said clutch capable of slipping when subject to a torque in excess of that predetermined, and adjusting means, operable while said clutch is in motion, whereby the torque at which it will slip may be predetermined.

25. A well drilling rig, including a rotary table capable of rotating a drill pipe, a hoist capable of raising and lowering the drill pipe, a power shaft operatively connected to and capable of operating said table and said hoist simultaneously, and a clutch interposed between said hoist and said power shaft; said clutch capable of slipping when subject to a torque in excess of that predetermined, and adjusting means, operable while said clutch is in motion, whereby the torque at which it will slip may be predetermined.

26. In a drilling rig, including a rotary table capable of rotating a drill pipe, and an auxiliary power driven apparatus, a power shaft operatively connected to and capable of operating said table and said auxiliary simultaneously; and a clutch interposed between said power shaft and said table; said clutch capable of slipping when subject to a torque in excess of that predetermined, and adjusting means, operable while said clutch is in motion, whereby the torque at which it will slip may be predetermined.

27. In a well drilling rig, including a rotary table, and a power shaft for driving said table, a clutch interposed between the power shaft and the rotary table; said clutch capable of slipping when a predetermined torque is exceeded.

28. In a well drilling rig, including a rotary table, and a power shaft capable of rotating said table, a clutch interposed between said power shaft and said rotary table; said clutch capable of slipping when a predetermined torque is exceeded, and adjusting means operable while said clutch is in motion, whereby the torque at which said clutch will slip may be predetermined.

29. A well drilling rig, including a rotary table capable of rotating a drill pipe, a power shaft operatively connected to said rotary table, a clutch and a multiple gear transmission interposed between said power shaft and said rotary table in the order named; said clutch capable of slipping when a predetermined torque is exceeded.

30. A well drilling rig, including a rotary table capable of rotating a drill pipe, a power shaft operatively connected to said rotary table, a clutch and a multiple gear transmission interposed between said power shaft and said rotary table in the order named; said clutch capable of slipping when a predetermined torque is exceeded, and adjusting means on said clutch operable while the clutch is in motion, whereby the torque at which the clutch will slip may be predetermined.

31. A well drilling rig, including a rotary table capable of rotating a drill pipe, a hoist capable of raising and lowering said drill pipe, a power shaft operatively connected to and capable of operating said hoist and said table simultaneously, a clutch and multiple gear transmission interposed between said power shaft and said table in the order named, another clutch and another multiple gear interposed between said power shaft and said hoist in the order named; said clutches capable of slipping when a predetermined torque is exceeded.

32. A well drilling rig, including a rotary table capable of rotating a drill pipe, a hoist capable of raising and lowering said drill pipe, a power shaft operatively connected to and capable of operating said hoist and said table simultaneously, a clutch and multiple gear transmission interposed between said power shaft and said table in the order named, another clutch and another multiple gear interposed between said power shaft and said hoist in the order named, said clutches capable of slipping when a predetermined torque is exceeded, and adjusting means for each clutch whereby the torque at which they will slip may be predetermined; said means capable of operation while a clutch is in motion.

33. A well drilling rig, including a rotary table capable of rotating a drill pipe, a hoist capable of raising and lowering the drill pipe, a mud pumping device, a power shaft operatively connected to and capable of rotating said rotary table, said hoist and

said mud pumping device simultaneously, a multiple gear interposed between said rotary table and said power shaft, and another multiple gear interposed between said hoist and 5 said power shaft, and a governor controlled prime mover, whereby said mud pumping device may be operated at constant speed in one direction regardless of the speed or direction in which said rotary table and 10 said hoist are running.

34. A well drilling rig, including a rotary table capable of rotating a drill pipe, a hoist capable of raising and lowering the drill pipe, a mud pumping device, a power 15 shaft operatively connected to and capable of rotating said rotary table, said hoist and said mud pumping device simultaneously, and a multiple gear interposed between said rotary table and said power shaft, and a 20 governor controlled prime mover, whereby said mud pumping device may be operated at a constant speed in one direction regardless of the speed or direction in which said rotary table and said hoist are running.

35. A well drilling rig, including a rotary table capable of rotating a drill pipe, a hoist capable of raising and lowering the drill pipe, a mud pumping device, a power shaft operatively connected to and capable of 25 rotating said rotary table, said hoist and said mud pumping device simultaneously, and a multiple gear interposed between said hoist and said power shaft, and a governor controlled prime mover, whereby said mud 30 pumping device may be operated at a constant speed in one direction regardless of the speed or direction in which said rotary table and said hoist are running.

36. A well drilling rig, including a rotary 40 table capable of rotating a drill pipe, a hoist capable of raising and lowering the drill pipe, a mud pumping device, a power shaft operatively connected to and capable of rotating said rotary table, said hoist and said mud 45 pumping device simultaneously, a multiple gear interposed between said rotary table and said power shaft, and another multiple gear interposed between said hoist and said power shaft; said multiple gears 50 each having a plurality of forward speed positions, a neutral position and a reverse position, and a governor controlled prime mover, whereby said mud pumping device may be operated at constant speed in one direction regardless of the speed or direction 55 in which said rotary table and said hoist are running.

37. A well drilling rig, including a rotary 60 table capable of rotating a drill pipe, a hoist capable of raising and lowering the drill pipe, a mud pumping device, a power shaft operatively connected to and capable of rotating said rotary table, said hoist and said mud pumping device simultaneously, 65 and a multiple gear interposed between said

rotary table and said power shaft; said multiple gear having a plurality of forward speed positions, a neutral position and a reverse position, and a governor controlled prime mover, whereby said mud pumping device may be operated at a constant speed in one direction regardless of the speed or direction in which said rotary table and 70 said hoist are running.

38. A well drilling rig, including a rotary 75 table capable of rotating a drill pipe, a hoist capable of raising and lowering the drill pipe, a mud pumping device, a power shaft operatively connected to and capable of rotating said rotary table, said hoist and said mud pumping device simultaneously, and a multiple gear interposed between said hoist and said power shaft; said multiple gear having a plurality of forward speed 80 positions, a neutral position and a reverse position, and a governor controlled prime mover; whereby said mud pumping device may be operated at a constant speed in one direction regardless of the speed or direction 85 in which said rotary table and said hoist are running.

39. A well drilling rig, including a rotary 90 table capable of rotating a drill pipe, a hoist capable of raising and lowering the drill pipe, a power shaft operatively connected to and capable of operating said rotary table and said hoist simultaneously, a multiple gear interposed between said rotary table and said power shaft, and another multiple gear interposed between said hoist and said power shaft, and a governor controlled prime mover; whereby said table may be 95 operated at maximum speed while said hoist is running at less than maximum speed, and whereby said hoist may be operated at maximum speed while said table is running at less than maximum speed.

40. A well drilling rig, including a rotary 100 table capable of rotating a drill pipe, a hoist capable of raising and lowering said drill pipe, a power shaft operatively connected to and capable of operating said rotary table and said hoist simultaneously, and a multiple gear interposed between said rotary table and said power shaft, and a governor controlled prime mover; whereby said table may be operated at maximum speed while said hoist is running less than maximum speed, and whereby said hoist may be operated at maximum speed while said table is 105 running at less than maximum speed.

41. A well drilling rig, including a rotary 110 table capable of rotating a drill pipe, a hoist capable of raising and lowering said drill pipe, a power shaft operatively connected to and capable of operating said rotary table and said hoist simultaneously, and a multiple gear interposed between said hoist and said power shaft, and a governor controlled prime mover; whereby said table 115

may be operated at maximum speed while said hoist is running at less than maximum speed, and whereby said hoist may be operated at maximum speed while the table 5 is running at less than maximum speed.

42. A well drilling rig, including a rotary table capable of rotating a drill pipe, a hoist capable of raising and lowering said drill pipe, a power shaft operatively connected to 10 and capable of operating said rotary table and said hoist simultaneously, and a multiple gear interposed between said hoist and said power shaft, and another multiple gear interposed between said rotary table and 15 said power shaft; said multiple gears each having a plurality of forward speed positions, a neutral position and a reverse position, and a governor controlled prime mover; whereby said table may be operated 20 at a maximum speed while the said hoist is running at less than maximum speed, and whereby said hoist may be operated at maximum speed while said table is running at less than maximum speed.

43. A well drilling rig, including a rotary table capable of rotating a drill pipe, a hoist capable of raising and lowering said drill pipe, a power shaft operatively connected to 25 and capable of operating said rotary table and said hoist simultaneously; and a multiple gear interposed between said rotary table and said power shaft; said multiple gear having a plurality of forward speed positions, a neutral position and a reverse 30 position, a governor controlled prime mover, whereby said table may be operated at a maximum speed while said hoist is running at less than maximum speed, and whereby said hoist may be operated at maximum 35 speed while said table is running at less than maximum speed.

44. A well drilling rig, including a rotary table capable of rotating a drill pipe, a hoist capable of raising and lowering said drill 45 pipe, a power shaft operatively connected to and capable of operating said rotary table and said hoist simultaneously, and a multiple gear interposed between said hoist and said power shaft, said multiple gear having 50 a plurality of forward speed positions, a neutral position and a reverse position, and a governor controlled prime mover, whereby said table may be operated at maximum speed while said hoist is running at less than maximum speed, and whereby said hoist 55 may be operated at maximum speed while said table is running at less than maximum speed.

45. A well drilling rig, including a rotary 60 table capable of rotating a drill pipe, a hoist capable of raising and lowering the drill pipe, a pumping device, a power shaft operatively connected to and capable of operating said table, said hoist and said pump simultaneously, a clutch interposed between

said power shaft and said rotary table, a second clutch interposed between said power shaft and said hoist, and a third clutch interposed between said power shaft and said mud pumping device; each of said clutches 70 being capable of slipping when subject to a torque in excess of that predetermined, and a governor controlled prime mover driving said power shaft; whereby tendency on the part of the rotary table, hoist or mud pumping device to stall the prime mover will be obviated.

46. A well drilling rig, including a rotary table capable of rotating a drill pipe, a hoist capable of raising and lowering the 80 drill pipe, a pumping device, a power shaft operatively connected to and capable of operating said table, said hoist and said pump simultaneously, and a clutch interposed between said power shaft and said rotary table; said clutch capable of slipping when subject to a torque in excess of that predetermined, and a governor controlled prime mover for driving said power shaft; whereby a force acting to retard or stop will not 85 stall the prime mover so that pump and hoist may continue in operation at usual speed.

47. A well drilling rig, including a rotary table capable of rotating a drill pipe, a hoist 90 capable of raising and lowering the drill pipe, a pumping device, a power shaft operatively connected to and capable of operating said table, said hoist and said pump simultaneously, and a clutch interposed between said power shaft and said hoist; said clutch capable of slipping when subject to a torque in excess of that predetermined, and a governor controlled prime mover for driving 95 said power shaft; whereby a force acting on said hoist and tending to stall it will not stall the prime mover.

48. A well drilling rig, including a rotary table capable of rotating a drill pipe, a hoist capable of raising and lowering the drill pipe, a pumping device, a power shaft operatively connected to and capable of operating said table, said hoist and said pump simultaneously, and a clutch interposed between said power shaft and said pumping device; said clutch capable of slipping when subject to a torque in excess of that predetermined, and governor controlled prime mover for driving said power shaft, whereby stoppage of the mud pumping device will not 110 stall the prime mover.

49. A well drilling rig, including a rotary table capable of rotating a drill pipe, a hoist capable of raising and lowering the drill pipe, a power shaft operatively connected to and capable of operating said table and said hoist simultaneously, and a clutch interposed between said rotary table and said power shaft; said clutch capable of slipping 115 when subject to a torque in excess of that 120

predetermined, and a governor controlled prime mover for driving said power shaft; whereby a force acting to stop said drill pipe will not stall said prime mover, and where-
5 by the said hoist may be brought into op-
eration even after the drill pipe has been stopped.

50. In a well drilling rig, including a ro-
10 tary table capable of rotating a drill pipe, and an auxiliary power driven apparatus, a power shaft operatively connected to and capable of operating said table and said aux-
iliary simultaneously, and a clutch inter-
posed between said power shaft and said
15 table; said clutch capable of slipping when subject to a torque in excess of that prede-
termined, and a governor controlled prime mover for driving the power shaft; whereby
said auxiliary will continue to be driven by
20 the prime mover should a force act to stop said drill pipe.

51. A well drilling rig, including a rotary table capable of rotating a drill pipe, a hoist capable of raising and lowering the drill
25 pipe, a pumping device, a power shaft oper-
atively connected to and capable of oper-
ating said table, said hoist and said pump si-
multaneously, a clutch interposed between
30 said power shaft and said rotary table, a
second clutch interposed between said power
shaft and said hoist, and a third clutch in-
terposed between said power shaft and said
35 pumping device; each of said clutches being
capable of slipping when subject to a torque
in excess of that predetermined, and adjust-
ing means operable while said clutches are
40 in motion, whereby the torque at which they
will slip may be predetermined, and a gov-
ernor controlled prime mover for driving
said shaft.

52. A well drilling rig, including a rotary table capable of rotating a drill pipe, a hoist capable of raising and lowering the drill pipe, a pumping device, a power shaft oper-
45 atively connected to and capable of oper-
ating said table, said hoist and said pump si-
multaneously; and a clutch interposed be-
tween said power shaft and said rotary ta-
ble; said clutch capable of slipping when
50 subject to a torque in excess of that predeter-
mined, and adjusting means, operable when
said clutch is in motion, whereby the torque
at which it will slip may be predetermined,
and a governor controlled prime mover for
55 driving said shaft.

53. A well drilling rig, including a rotary table capable of rotating a drill pipe, a hoist capable of raising and lowering the drill pipe, a pumping device, a power shaft oper-
60 atively connected to and capable of oper-
ating said table, said hoist and said pump si-
multaneously, and a clutch interposed be-
tween said power shaft and said hoist; said
65 clutch capable of slipping when subject to a
torque in excess of that predetermined, and

adjusting means, operable while said clutch
is in motion, whereby the torque at which it
will slip may be predetermined, and a gov-
ernor controlled prime mover for driving
70 said shaft.

54. A well drilling rig, including a rotary table capable of rotating a drill pipe, a hoist capable of raising and lowering the drill pipe, a pumping device, a power shaft operatively connected to and capable of operating said table, said hoist and said pump simultaneously, and a clutch inter-
posed between said power shaft and said pumping device; said clutch capable of slipping when subject to a torque in excess of
75 that predetermined, and adjusting means,
operable while said clutch is in motion,
whereby the torque at which it will slip
may be determined, and a governor con-
trolled prime mover for driving said shaft.
80

55. A well drilling rig, including a rotary table capable of rotating a drill pipe, a hoist capable of raising and lowering the drill pipe, a power shaft operatively connected to and capable of operating said table and said hoist simultaneously, and a clutch interposed between said rotary table and said power shaft; said clutch capable of slipping when subject to a torque in ex-
90 cess of that predetermined, and adjusting
means, operable while said clutch is in motion,
whereby the torque at which it will slip
may be predetermined, and a governor con-
trolled prime mover for driving said
95 shaft.

56. A well drilling rig, including a rotary table capable of rotating a drill pipe, a hoist capable of raising and lowering the drill pipe, a power shaft operatively connected to and capable of operating said table and said hoist simultaneously, and a clutch interposed between said hoist and said power shaft; said clutch capable of slipping when subject to a torque in excess
100 of that predetermined, and adjusting means,
operable while said clutch is in motion,
whereby the torque at which it will slip may
be predetermined, and a governor controlled
prime mover for driving said shaft.
105

57. In a well drilling rig, including a ro-
tary table capable of rotating a drill pipe,
and an auxiliary power driven apparatus,
a power shaft operatively connected to and
capable of operating said table and said
auxiliary simultaneously; and a clutch in-
terposed between said power shaft and said
table; said clutch capable of slipping when
subject to a torque in excess of that prede-
termined, and adjusting means, operable
when said clutch is in motion, whereby the
torque at which it will slip may be prede-
termined, and a governor controlled prime
mover for driving said shaft.
115

58. In a well drilling rig, including a ro-
tary table, and a power shaft for driving
120

- 5 said table, a clutch interposed between the power shaft and the rotary table; said clutch capable of slipping when a predetermined torque is exceeded, and a governor controlled prime mover driving said power shaft, whereby a force acting to stop said table will not stall said prime mover, and whereby twist-off of the drill pipe is prevented.
- 10 59. A well drilling rig, including a rotary table capable of rotating a drill pipe, a power shaft operatively connected to said rotary table, a clutch and multiple gear transmission interposed between said power shaft and said rotary table in the order named; said clutch capable of slipping when a predetermined torque is exceeded, and a governor controlled prime mover for driving said power shaft.
- 15 60. A well drilling rig, including a rotary table capable of rotating a drill pipe, a power shaft operatively connected to said rotary table, a clutch and a multiple gear transmission interposed between said power shaft and said rotary table in the order named; said clutch capable of slipping when a predetermined torque is exceeded, and adjusting means on said clutch operable while the clutch is in motion, whereby the torque 20 at which the clutch will slip may be predetermined, and a governor controlled prime mover for driving said shaft; all operable in the manner and for the purpose set forth.
- 25 61. A well drilling rig, including a rotary table capable of rotating a drill pipe, a hoist capable of raising and lowering said drill pipe, a power shaft operatively connected to and capable of operating said hoist and said table simultaneously, a clutch and multiple gear transmission interposed between said power shaft and said table in the order named, another clutch and another multiple gear interposed between said power shaft and said hoist in the order named; said clutches capable of slipping when a predetermined torque is exceeded; and a governor prime mover driving said power shaft; all operating in the 30 same manner and for the purpose set forth.
- 35 62. A well drilling rig, including a rotary table capable of rotating a drill pipe, a hoist capable of raising and lowering said drill pipe, a power shaft operatively connected to and capable of operating said hoist and said table simultaneously, a clutch and multiple gear transmission interposed between said power shaft and said table in the order named, another clutch and another multiple gear transmission interposed between said power shaft and said hoist in the order named; said clutches capable of slipping when a predetermined torque is exceeded, and adjusting means for each clutch whereby the torque at which they will slip may 40 be predetermined; said means capable of operation while a clutch is in motion, and a governor controlled prime mover for driving said shaft; all operating in the manner and for the purpose set forth. 70
- 45 63. A well drilling rig, including a rotary table capable of rotating a drill pipe, a hoist capable of raising and lowering the drill pipe, a mud pumping device, a power shaft operatively connected to and capable of driving said table, hoist and mud pumping device, a governor controlled prime mover for driving said power shaft, a multiple gear transmission interposed between said rotary table and said power shaft, manually operated control means acting on said governor to vary the speed of the prime mover regardless of the load. 75
- 50 64. A well drilling rig, including a rotary table capable of rotating a drill pipe, a hoist capable of raising and lowering the drill pipe, a mud pumping device, a power shaft operatively connected to and capable of operating said rotary table, said hoist and said mud pumping device simultaneously, a governor controlled prime mover for driving said power shaft, a multiple gear transmission interposed between said power shaft and said rotary table, and manually controlled means operating on said governor to 80 vary the speed of the prime mover. 90
- 55 65. A well drilling rig, including a rotary table capable of rotating a drill pipe, a hoist capable of raising and lowering the drill pipe, a mud pumping device, a power shaft operatively connected to and capable of operating said rotary table, said hoist and said mud pumping device simultaneously, a governor controlled prime mover for driving said power shaft, a multiple gear transmission interposed between said power shaft and said rotary table, manually controlled means operating on said governor to 100 vary the speed of the prime mover, and a multiple gear transmission interposed between said power shaft and said hoist. 105
- 60 66. A well drilling rig, including a rotary table capable of rotating a drill pipe, a hoist capable of raising and lowering said drill pipe, a power shaft operatively connected to and capable of driving said table and said hoist, a multiple gear transmission and a clutch interposed between said table and said power shaft, said clutch capable of slipping when a predetermined torque is exceeded, a governor controlled prime mover for driving said power shaft, and manually operated control means acting on said governor to vary the speed of said power shaft. 110 115
- 65 67. A well drilling rig, including a rotary table capable of rotating a drill pipe, a mud pumping device, a power shaft operatively connected to and capable of driving said pumping device and said table simultaneously, a clutch interposed between said 120 power shaft and said table. 125

power shaft and said rotary table, a governor controlled prime mover for driving said power shaft, and manually controlled means acting on said governor to vary the speed 5 of said power shaft.

68. A well drilling rig, including a rotary table capable of rotating a drill pipe, a mud pumping device, a power shaft operatively connected to and capable of driving said pumping device and said table simultaneously, a clutch interposed between said power shaft and said rotary table, a governor controlled prime mover for driving said power shaft, manually controlled means acting 10 on said governor to vary the speed of said power shaft, a multiple gear transmission interposed between said clutch and said power shaft; said clutch capable of slipping when a predetermined torque is exceeded.
69. A well drilling rig, including a rotary table capable of rotating a drill pipe, a power shaft operatively connected to and capable of driving said rotary table, a plurality 15 of governor controlled prime movers for driving said power shaft, clutches interposed between each of said prime movers, whereby any or all of said prime movers may be caused to drive said shaft or be de-clutched from operative connection therewith at the will of the operator of the rig.

70. A well drilling rig, including a rotary table capable of rotating a drill pipe, a power shaft operatively connected to and capable of driving said rotary table, a plurality 20 of governor controlled prime movers for driving said power shaft, clutches interposed between each of said prime movers, whereby any or all of said prime movers may be caused to drive said shaft or be de-clutched from operative connection therewith at the will of the operator of the rig, a speed governor for each prime mover, and means 25 collectively acting on said governors to vary the speed of the prime movers then running.

71. A well drilling rig, including a rotary table capable of rotating a drill pipe, a power shaft operatively connected to and capable of driving said rotary table, a multiple gear transmission for said rotary table, a plurality 30 of governor controlled prime movers for driving said power shaft, clutches interposed between each of said prime movers and said power shaft, whereby any or all of said prime movers may be caused to drive said shaft or be de-clutched from operative connection therewith at the will of the operator of the rig, a speed governor for each prime mover, and means 35 collectively acting on said governor to vary the speed of the prime mover then running.

72. A well drilling rig, including a rotary table capable of rotating a drill pipe, a hoist capable of raising and lowering a drill pipe, a power shaft operatively connected to and capable of driving said rotary table, and 40

said hoist, a plurality of governor controlled prime movers for driving said power shaft, and clutches interposed between each of said prime movers and said power shaft, whereby any or all of said prime movers 45 may be caused to drive said shaft or be de-clutched from operative connection therewith at the will of the operator of the rig.

73. A well drilling rig, including a rotary table capable of rotating a drill pipe, a hoist capable of raising and lowering a drill pipe, a power shaft operatively connected to and capable of driving said rotary table, and said hoist, a plurality of governor controlled prime movers for driving said power shaft, 50 clutches interposed between each of said prime movers and said power shaft, whereby any or all of said prime movers may be caused to drive said shaft or be de-clutched from operative connection therewith at the will of the operator of the rig, a speed governor for each prime mover, and means for collectively acting on said governors to vary the speed of the prime movers then running.

74. A well drilling rig, including a rotary table capable of rotating a drill pipe, a hoist capable of raising and lowering a drill pipe, a power shaft operatively connected to and capable of driving said rotary table and said hoist, a multiple gear transmission for said hoist, a plurality of governor controlled prime movers for driving said power shaft, clutches interposed between each of said prime movers and said power shaft, whereby any or all of said prime movers may be 60 caused to drive said shaft or be de-clutched from operative connection therewith at the will of the operator of the rig, a speed governor for each prime mover, and means for collectively acting on said governors to vary 65 the speed of the prime movers then running.

75. A well drilling rig, including a rotary table capable of rotating a drill pipe, a power shaft operatively connected to and capable of driving said rotary table, clutches interposed between said power shaft and said table, a plurality of governor controlled prime movers for driving said power shaft, and clutches interposed between each of said prime movers and said power shaft whereby 70 any or all of said prime movers may be caused to drive said shaft or be de-clutched from operative connection therewith at the will of the operator of the rig.

76. A well drilling rig, including a rotary table capable of rotating a drill pipe, a power shaft operatively connected to and capable of driving said rotary table, clutches interposed between said power shaft and said table, a plurality of governor controlled 75 prime movers for driving said power shaft, clutches interposed between each of said prime movers and said power shaft whereby any or all of said prime movers may be caused to drive said shaft or be de-clutched 80

- from operative connection therewith at the will of the operator of the rig, a speed governor for each prime mover, and means for collectively acting on said governors to vary the speed of the prime movers then running. 5
77. A well drilling rig, including a rotary table capable of rotating a drill pipe, a hoist capable of raising and lowering said drill pipe, a power shaft operatively connected to and capable of driving said rotary table and said hoist, a clutch interposed between said power shaft and said table, and a clutch interposed between said power shaft and said hoist, a multiple gear transmission for said rotary table, a multiple gear transmission for said hoist, a plurality of governor controlled prime movers for driving said power shaft, clutches interposed between each of said prime movers 10 and said power shaft whereby any or all of said prime movers may be caused to drive said shaft or be de-clutched from operative connection therewith at the will of the operator of the rig, a speed governor for each 15 prime mover, and means for collectively acting on said governors to vary the speed of the prime movers then running. 20
78. A well drilling rig, including a rotary table capable of rotating a drill pipe, a hoist capable of raising and lowering said drill pipe, a mud pumping device, a power shaft operatively connected to and capable of driving said rotary table, said hoist and said mud pumping device, a clutch interposed between said power shaft and said table, a second clutch interposed between said power shaft and said hoist, and another clutch interposed between said power shaft and said mud pumping device, a multiple gear transmission for said rotary table, a multiple gear transmission for said hoist, a governor controlled prime mover for driving said power shaft, clutches interposed between each of said prime movers and said power shaft whereby any or all of said prime movers may be caused to drive said shaft or be de-clutched from operative connection therewith at the will of the operator of the rig, a speed governor for each prime mover, and means for collectively acting on said governors to vary the speed of the prime movers then running. 25
79. A power plant for drilling rigs and the like, including a plurality of engines, a power shaft, and means for selectively connecting one or more of said engines to said power shaft. 30
80. A power plant for drilling rigs and the like, including a plurality of prime movers, a power shaft one of said prime movers extending in longitudinal alignment with said power shaft, the other of said prime movers radially disposed with the first of said prime movers about a common center, and means for selectively connecting or disconnecting one or more of said engines with said shaft. 35
81. A power plant for drilling rigs and the like, including three prime movers, one of said prime movers in alignment with and capable of driving said power shaft directly, a bevel gear carried on said power shaft; the other of said prime movers disposed at right angles to and on either side of said power shaft, a bevel gear driven by each of said other two prime movers, and meshing with the bevel gear on said power shaft, and a clutch for each of said prime movers disposed between it and its bevel gear. 40
82. A power plant for drilling rigs and the like, including a plurality of engines, a power shaft, and means for selectively connecting one or more of said engines to said power shaft, a speed governor on each engine, and means for controlling all governors jointly. 45
83. A power plant for drilling rigs and the like, including a plurality of prime movers, one of said prime movers extending in longitudinal alignment with said power shaft, the other of said prime movers radially disposed with the first of said prime movers about a common center, and means for selectively connecting or disconnecting one or more of said prime movers with said shaft, a speed governor on each prime mover, and means for controlling all governors jointly. 50
84. A power plant for drilling rigs and the like, including three prime movers, one of said prime movers in alignment with and capable of driving said power shaft directly, a bevel gear carried on said power shaft; the other of said prime movers disposed at right angles to and on either side of said power shaft, a bevel gear driven by each of said other two prime movers, and meshing with the bevel gear on said power shaft, and a clutch for each of said prime movers disposed between it and its bevel gear, a speed governor on each prime mover and means for controlling all governors jointly. 55

WILLIAM SYLVESTER GREGORY.
